UNITED STATES PATENT OFFICE.

JOHN E. LUNDQUIST, OF CHICAGO, ILLINOIS.

COMBINATION TOOL.

Application filed January 14, 1921. Serial No. 437,188.

To all whom it may concern:

Be it known that I, JOHN E. LUNDQUIST, a citizen of the United States, residing at Chicago, in the county of Cook and State 5 of Illinois, have invented certain new and useful Improvements in Combination Tools, of which the following is a specification.

The invention relates to combination tools, and more particularly to hand instruments 10 having special utility in measuring, gauging and laying out work in the mechanical crafts.

The invention consists of a novel construction and combination of parts so arranged and inscribed as to be useful to 15 machinists, draftsmen, and all metal and wood workers.

Its object is to provide a light, compact instrument, capable of being readily adjusted and conveniently carried, which comprises a minimum number of integral parts adapted to a large variety of uses, and which is of simple construction so that it may be 20 cheaply manufactured.

25 In the drawings, Figure 1 is a view of one side of the device with its arms partially open. Figure 2 is a view of the reverse side with the arms in a different partially open position. Figure 3 represents 30 the instrument with its arms extended. Figure 4 is a side view in extended position.

The device comprises dividers, outside 35 calipers, inside calipers, center gauge, screw cutting tool gauge, stationary left hand square, stationary right hand square, combination angle square, protractor, wire gauge, hook rule, 8" rule graduated in thirty-seconds of an inch reading to left and to right, rule graduated in sixtieths of 40 an inch, rule graduated in hundredths of an inch, metric rule, scale for screw threads, and inscribed tables of useful purpose.

The device is constructed with two main 45 parts, designated in the drawings as 1 and 2, pivotally joined by the pivot bolt 3. Each of the parts 1 and 2 is formed of flat material, preferably sheet metal, with a semi-circular center portion 4 from which 50 extends a plurality of integral projections shaped suitably to the several functions of the tool. Thus, elongated radial blades 10 and 12 terminate in pointed ends 14 and 16 forming a pair of dividers. Oppositely 55 from said blades of the dividers the radial

legs 18 and 20 are extended having oppositely curved ends. In the position represented in Fig. 1 the legs 18 and 20 form outside calipers, while in the position illustrated in Fig. 2 they form inside calipers, the change 60 being accomplished merely by swinging the parts 1 and 2 from the position shown in Fig. 1 together and then apart again but into reverse angular relation. Protractor scales 22 and 26 are provided by inscription 65 on the center portion 4 of part 2 (Fig. 2) which scales are appropriately divided for use in caliper. The scale 22 is read in connection with an indicator point 24 formed on the center portion 4 of part 1 when 70 caliper inside dimensions, and the scale 26 is used in connection with a point 28 when caliper outside surfaces.

A lateral projection 30 is formed on part 2, and has its end notched at 32 to form a 75 standard angle center gauge suitable to gauge the grinding of lathe centers. Along its edges on both faces of the projection 30 are inscribed scales 34, 34^a, 34^b and 34^c for measuring the number of screw threads to se an inch. Oppositely disposed on part 1 is a projection 36 having the edges of its pointed end forming the same angle as formed by the notch 32, thus serving as a gauge for the counter bore in work to be 85 centered in a lathe. The projection 36 may also be used as a depth gauge as the extent to which its pointed end may be entered in a counterbore, for example, will obviously give an indication of the depth of the latter. 90 The notches 38 form standard angles convenient for gauging the grinding of screw cutting tools. Any useful table of mechanical data may be inscribed on the faces of the projection 36, in the present case a 95 table of tap drill sizes is indicated at 40 (Fig. 1).

The outer edges of the projections 30 and 36 form right angles at 42 and 44 with the intersecting edges of the blades 12 and 10 100 respectively. With respect to the scales inscribed on the blades, there are thus provided a left hand square and a right hand square. With the parts 1 and 2 in the relation illustrated in Fig. 1, it will be ob- 105 served that the inner edges of the blades 10 and 12 intersect, and that by swinging the blades on their common pivot any desired angular relation between them may be obtained. The blades may be secured in 110

such angular relation by tightening the pivot bolt 3, and the tool used as a combination angle square.

A circular scale 46 is inscribed on one face 5 of part 1, by which the degrees of angular separation of the blades 10 and 12 may be read as indicated at the point 48 which is formed on part 2 and passes over the arc as the blades are moved on their pivot. By 10 this means the instrument is adapted to be used as a protractor.

The curved edges of the center portions 4 of the main parts are provided with openings 50, which form a metal and wire gauge. 15 On the adjoining surface on the center portion of one of the parts is inscribed a table of wire sizes, 51 (Fig. 2).

A hook 52 is mounted on the blade 12 by means of a pivot stud 54, and may be swung 20 into or out of operative position about its pivot. As illustrated in Fig. 1 and Fig. 3, the projecting hook and the blade 12 form a convenient hook rule. Preferably a slight projection 52^a is provided on the part 2 to 25 form a stop to resist the swinging movement of the hook. This projection is so located that it serves to hold the hook either in its operative or inoperative position. The hook, it will be seen, is mounted so that its free end may be engaged by the fingers to spring the same over the projection 52^a. Thus the hook is held yieldingly by the projection against pivotal movement.

It is apparent that the faces of the instrument, particularly of the blades 10 and 12 may be inscribed with any desired graduated scales and tables. In the present embodiment the blade 10 is inscribed on one surface to form on one edge a rule 56 graduated to sixty-fourths of an inch and on the opposite edge a rule 58 graduated to one-hundredths of an inch. Both edges of one surface of blade 12 are inscribed for use as metric rules 60 and 61.

On the opposite surfaces of the blades 10 and 12, and along the continuous straight edges of the central portions, the scales 62, graduated to thirty-seconds of an inch, are inscribed. By swinging the two blades into 50 position oppositely from their pivot, with their outer edges forming a straight line (Fig. 3), the scales 62 form a continuous 8 inch rule, and are inscribed to be read to the right or left.

It is apparent from the description that 55 the invention provides a great variety of useful tools combined in one simple implement convenient to use and carry, and that its simple parts may be cheaply manufactured.

While I have herein described the invention with considerable particularity, it will be understood that I do not intend to be limited in the interpretation of the appended claims to the construction and arrangement 60 set forth, except as may be necessitated by the state of the prior art.

I claim as my invention:

1. A combination tool having, in combination, two flat body members disposed in 70 overlapping relation, a stud connecting said members for relative pivotal movement, a blade element on each of said members extending radially from said stud and having a curved outer end, said blade elements having their curved ends disposed either toward or away from each other according to selected positions of said members, there being two arcuate scales arranged on one of said members concentric with said stud, and two 75 indicator points on the other member, one registering with one of said scales when said curved ends are disposed toward each other and the other registering with said other scale when said curved ends are disposed 80 away from each other.

2. A combination tool having, in combination, two body members formed from sheet metal, a pivot bolt connecting said members in overlapping relation and adapting them for relative rotation, a pair of blade elements having straight edges, one 90 on each of said members extending radially from said pivot bolt, one edge of one of said elements intersecting one edge of the 95 other element through one half of a revolution of said members, said intersecting edges forming a continuous straight edge when said elements are rotated into alinement, there being a graduated scale along opposite longitudinal edges of said elements, the scales on one longitudinal edge of each of said elements being adapted to read continuously along said straight edge.

In testimony whereof, I have hereunto set 100 my hand.

JOHN E. LUNDQUIST.
